TELEPHONE SWITCH

Konrad Müller, Berlin-Spandau, Germany, assignor to Siemens & Halske Aktiengesellschaft, Siemensstadt, near Berlin, Germany

Application September 21, 1936, Serial No. 101,825
In Germany September 26, 1935

2 Claims. (Cl. 179—27.51)

The subject of the invention is a rotary selector, more especially for use in telephone systems, of the type in which the wipers associated with the speaking leads remain out of contact with the bank contacts while the switch is being set.

By means of the free movement of the stepping wipers of such selectors a reduction is effected in the noise made by the selector and furthermore the wipers are exposed to less wear. A further advantage of such switches consists in that the wipers associated with the speaking leads and the bank contacts associated with these wipers can be provided with expensive noble metal contacts thereby producing greater efficiency in contacting.

According to the invention it is proposed to effect the raising of the wipers associated with the speaking leads from the bank contacts by a magnet, while the wipers are pressed into engagement with the contacts by means of a spring which is subjected to tension by this magnet. Thus, in contradistinction to the known proposals of this sort, the wiper magnets are only brought into use for a short time, namely, only during the relatively short time occupied by the setting and releasing motions, the smallest number of additional means being necessary.

The invention is represented by way of embodiment in Figs. 1 and 2 of the drawings. Fig. 1 shows the arrangement in the rest position and Fig. 2 shows the operating position. In the figures only those parts of the set are shown which are necessary to enable the invention to be understood.

Fig. 3 shows a particular construction of the wipers associated with the speaking leads at the ends which contact with the bank contacts.

Fig. 4 shows a guarding device in the wiper set for preventing the wipers being displaced by hand when the wipers associated with the speaking leads are in contact with the bank contacts.

Fig. 5 shows a circuit for such a switch provided with a wiper magnet which is motor driven and operates as a group selector.

The switch shown in Figs. 1 and 2 comprises the wiper set which is displaceably mounted on the shaft 1 and is set in rotation over a toothed disc 2 by the driving wheels 3 of a driving mechanism which is not shown. The wipers 4 of the wiper set represent the wipers associated with the speaking leads and as may be seen from Fig. 3 are slotted at the working end in the same way as a relay spring and are provided with double contacts 5 formed of noble metal. The other wipers 6 of the wiper set are constructed as

double wipers in the usual way. Only a part of the contact bank which is indicated by the reference 7 is shown. All the bank contacts 8 which are associated with the wipers 4 connected to the speaking leads likewise possess contacts 9 formed of noble metal arranged at the point which make contact with these wipers.

At the lower side of the plate 10 of the selector which carries a switching shaft 1 an electromagnet is arranged which will be referred to in the following description as the wiper magnet BU. It is constructed as a flat relay in order to produce a compact arrangement having satisfactory magnetic properties, being provided with a flat core and an armature 11 arranged laterally with respect thereto. The armature carries a bent member 12 to whose upper portion is attached a spring 13 which is mounted on the upper surface of the plate 10. If a different mounting is preferable the spring can, of course, consist for example, of a helical spring. The bent member 12 is pressed against a disc 14 rigidly fixed to the wiper set when the wiper magnet is deenergized so that the wiper set which is displaceably mounted on the shaft 1 is displaced as far as the disc 15 at the upper end of the shaft 1, which disc forms a stop in the normal condition of the switch (Fig. 1) so that the wipers 4 associated with the speaking leads move from their normal position and at their noble metal contacts 5 press against the bank contact strips 8 which are similarly provided with noble metal contacts 9. The double wipers 6 of the wiper set accompany this displacement on account of their spring attachments.

When the switch is being set the wiper magnet BU is energized. The armature 11 when attracted carries with it the bent member 12 against the pressure of the spring 13 and thereby releases the wiper set. Accordingly, the wiper set can now drop down while it is pressed by the current conducting springs 16 of the wiper against the bush 17 at the lower end of the shaft 1 (Fig. 2). At the same time, on the energizing of the wiper magnet BU contact 16bu is operated by the armature 11 whereby the circuit for the driving device of the selector is completed or prepared. Since the wipers 4 associated with the speaking leads are already out of contact with the bank contacts 8, the wipers can move freely between the bank contacts during the rotary movements which now take place without a loop being established between the points of contact 5 and the contact strips 8. The pressure of the spring 13 against the wiper set is re-

moved by the attracted armature 11 of the wiper magnet BU so that the wiper set rotates without any particular friction. The friction occurring at the bush 17 and the shaft 1 is small since only a portion of the guiding springs 16 operate on it.

When the switch is brought to rest after the wiper has found a free line the wiper magnet BU is again de-energized so that the spring 13 which is subject to tension in the operated position of the armature 11 returns the wiper set to the original position in which the points of contact 5 of the wipers 4 are pressed against the corresponding bank contacts 8 (Fig. 1).

15 When the switch is released the wiper magnet BU again energizes and it repeats the process already described of removing the wipers associated with the speaking leads while at the same time switching on the driving device, until the 20 selector has reached the rest position where on account of the deenergizing of the wiper magnet BU the wiper set again takes up the position shown in Fig. 1.

In order to prevent the wiper set from being 25 displaced by hand in this position a locking tooth 18 (Fig. 4) is arranged on the base plate 10 of the selector and engages with the teeth of disc 2 of the wiper set when this is in the elevated position. When the wiper magnet BU energizes 30 the toothed wheel 2 is displaced together with the wiper set on the shaft 1 so that the locking tooth 18 disengages with the teeth so that only now when the wiper set is in a position to allow the wipers associated with the speaking leads to 35 move freely between the bank contacts can the switch be rotated by the driving mechanism.

In Figure 5 is shown the circuit arrangement of the switch showing the wiper magnet and the driving arrangements. The switch shown 40 operates as a group selector. The switch can, of course, also be used in the same way in other switch stages of telephone systems. The mode of operation is as follows:

In describing the mode of operation of the 45 switch special importance is given to the manner in which the wiper magnet is operated. Details which are irrelevant to the fundamentals of the present case are omitted.

The motor switch provided with a wiper magnet BU has wipers *a*, *b*, *c*, and *d*. Of these wipers *a* and *b* are moved by the wiper magnet BU so that when the switch is stepped they do not contact with the bank contacts. The wipers *c* and *d* travel over their associated contact banks. When a free line has been found the wiper magnet releases and wipers *a* and *b* switch the line through. The motor is connected up by the wiper magnet BU. Any rotation of the switch with the *a* and *b* wipers not withdrawn 50 is thus definitely prevented. BU is only transitorily energized on the setting and release of the switch. The motor driven switch which operates as a group selector may be seized by a switch in the preceding switching stage, when relay C energizes in the following circuit: earth, battery, winding II of relay C, rotary off-normal contact 1w, earth in the preceding switch. Relay C, at contact 2c breaks the short-circuit over its winding I and locks up by closing contact 55 3c in a circuit independent of 1w. The energizing of relay C opens contacts 5c and 6c, contact 7c being then closed. This operation of the contacts has for the moment no influence on the switch. It will be assumed that one setting impulse is transmitted to the switch. The switch 60

will then search for a free-line in the first 10's level. By the setting impulses relay A which is provided with windings I, II and III is energized over the following circuit: earth, battery, resistance Wi, contact 4w, winding I of relay A, a lead, earth in the preceding switch. At this contact 8a, relay A opens the shunt around winding II of relay V and by closing contact 9a the circuit is closed for both windings of relay V. The closing of contact 10a and the opening of 10 contact 11a has no effect for the moment. The circuit of relay V runs as follows: earth, battery, windings I and II of relay V, rotary off-normal contact 12w, contact 9a, winding I of the repeater for the busy signal and earth. Relay 15 V energizes in this circuit and shunts contact 12w in this circuit by contact 13v. By the opening of contact 15v and the closing of contact 14v, the following circuit is closed for the wiper magnet BU: earth, battery, wiper magnet contact 14v 20 and earth. The wiper magnet energizes in this circuit and closes its contact 16bu and accordingly completes the circuit for the energizing winding MII of the driving motor of the switch. This circuit runs as follows: earth, battery, 25 winding MII of the motor, cam contact 17nk, contacts 16bu, 14v and earth. Current passes through winding MII and the armature of the motor is thereby moved as is also the switch. The motor operates in the known way in that 30 the nk contacts are controlled from its shaft and thereby alternatively subject the windings MI and MII of the motor to current. Wiper *d* of the switch moves out of the zero position into position 1. In this position in addition to winding MI of the motor which is then connected up over contact 18nk, winding MII is energized in the following circuit: earth, battery, winding MII, contacts 10a, position 1 of the switch, wiper *d*, contacts 16bu, 14v, and earth. Since both the 40 energizing windings of the switch are subjected to current the switch is brought to the rest position in the known way. When relay A falls back after the numerical impulse, contact 10a is opened and contact 11a closed. Through the 45 opening of contact 10a the circuit for winding MII is broken and the motor is switched on until in position 2 the following circuit is set up for winding MI: earth, battery MI, contacts 11a, 20v, 7c, wiper *d* in position 2, contacts 16bu, 50 14v and earth. In this position the line of the group in question is already closed. Not all the contacts in the switch levels are shown but only the important ones which play a part in the controlling of the switch within a group. 55 After the impulse or after an impulse train relay V falls back in the known way. When a number of impulses are transmitted relay V works as a slow acting relay on account of the short circuit established over contact 8a and 60 accordingly holds up throughout the impulse train. Over contacts 7v the damping windings MII, MI of the motor are connected up.

These windings are provided in order to enable the motor to run more slowly during the individual steps. Through the release of relay V testing potential is applied over contact 15v by way of earth, contact 25w, contacts 26v and 28p2 and the winding of relay P1 to wiper *c* of the switch. If the line is free, i. e., if battery potential is encountered, relay P1 energizes in this circuit. On account of the opening of contact 14v the wiper magnet BU is deenergized for a short time but is then again subjected to current over the following circuit: earth, battery, BU, 75

contact 15v, 47a, 28p2, 26v, 25w, earth. Relay P1 over its contact 40p1 establishes a shunt over winding MI and MII of the motor and thereby brings the motor to rest. Relay P1 in addition connects up windings I and II of the second testing relay P2 to wiper c of the switch over its contact 30p1. Relay P2 is accordingly connected up in parallel with relay P1 and energizes in the circuit described on account of battery on a free line in the next switch. The line seized is guarded against seizure on the part of another switch in the known way by the closing of contact 31p2. Relay P1 is disconnected by the opening of contact 27p2 and the closing of contact 31p2. The wiper magnet BU is disconnected by contact 28p2 so that wipers a and b are brought into contact with their contact bank. Contact 28p2 disconnects the motor. The call is switched through at contacts 35p2 and 36p2.

20 When conversation is completed the switch is released in the following way:

When the calling subscriber replaces the receiver the circuit for the seized relay C is broken. Relay C accordingly falls back. The closing of contact 5c establishes the following circuit for relay V: earth, battery, winding I of relay V, contacts 8a, 5c, 25w, earth. Relay V energizes in this circuit and at contact 14v again completes a circuit for the wiper magnet BU. Over this circuit the motor is transitorily connected up again.

The circuit for the motor is completed over contact 16bu. Since relay P1 has released the switch is stepped on by the motor. The switch travels to the zero position and is there brought to rest. Since relay C is deenergized contact 6c is now closed so that in addition to winding MII to which current is applied in the zero position of the switch winding MI is connected up in the following circuit: earth, battery, winding MI, contacts 11a, 29v, wiper d in position 0, contacts 16bu, 14v, earth. Through the opening of contact 25w relay V makes a delayed release. Relay V again disconnects the motor.

45 Positions 4 and 7 of the switch are dead positions. If the switch has found no free line in the selected group it passes to position 4 or 7 dependent upon the group in which the switch is searching. It is here brought to rest since 50 in addition the winding MI of the switch which

is then connected up over contact 18nk, winding of MII is energised in the following circuit: earth, battery, winding MII, contact 50v, winding III of relay A, wiper d in position 4 or 7, contacts 16bu, 15v, 27a, 28p2, 26v, 25w, earth. In this circuit relay A also energizes and at contact 41a disconnects the wiper magnet BU. Relay A locks up in the following circuit: earth, winding I of busy tone transformer, contacts 9a, 4tp2, winding II of relay A, winding III of relay A, contacts 10 50v, winding MII of motor, battery, earth. Over relay A the busy signal is transmitted by induction to the calling subscriber. Contacts 69a and 61v are closed while contact 62v is open.

The wiper magnet BU can be provided with further other contacts effecting other switching operations. Thus for example the wiper magnet can be connected up by the seizing relay and relay A can be connected to the a-lead over a contact of the wiper magnet. Moreover, it is possible to do away with the switching through contacts (35p2 and 36p2) and to effect the switching through directly by the disconnection of the wiper magnet and thereby through the a and b wipers.

What is claimed is:

1. In a non-numerical switch, a wiper set for said switch, bank contact sets accessible to said wipers, means for driving said wipers past said bank contact sets, a magnet and armature therefore, an energizing circuit for said magnet completed when the switch is seized, contacts controlled by the energization of said magnet for closing an operating circuit for said driving means, and means also controlled by the energization of said magnet for preventing said wipers from engaging said bank contact sets while the wipers are being controlled by said driving means.

2. In a non-numerical switch as claimed in claim 1, a set of test bank contacts, a test wiper controlled by said driving means to be advanced over successive contacts in said test bank, a test relay, a test circuit including said relay said test wiper and a particular one of said test contacts, means controlled by the energization of said test relay over said test circuit for disconnecting the energizing circuit for said magnet.

KONRAD MÜLLER.
